(57) **CLAIM**

The ornamental design for a book with spheres in transparent domes, as shown and described.

DESCRIPTION

FIG. 1 is a top front isometric view of a book with spheres in transparent domes, showing my new design;

FIG. 2 is a front elevational view thereof;

FIG. 3 is a back elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a top front isometric view of thereof, with the front cover in an open position;

FIG. 9 a top front isometric view of thereof, with the front cover in an open position and with several pages fanned open; and,

FIG. 10 top back isometric view thereof.

The spine portion, concentric circles on the front of the spheres, and the annular protrusions on the back of the spheres shown in broken lines are unclaimed environment, and form no part of the claimed design.
